ARC HEAD MECHANISM FOR
SEARCHLIGHTS

William H. Jacobi, Wilkinsburg, Pa., and Irvine A. Yest, Lakewood, Ohio, assignors to Westinghouse Electric & Manufacturing Company, East Pittsburgh, Pa., a corporation of Pennsylvania

Application June 19, 1937, Serial No. 149,156

8 Claims. (Cl. 176—117)

Our invention relates, generally, to arc searchlights, and, more particularly, to the construction of an arc head mechanism for high intensity arc searchlights.

5 In the operation of electric arc searchlights it is common practice to provide a mechanism for rotating the positive electrode to insure even burning of the electrode and for feeding the electrode to the arc to compensate for the con-

10 sumption of the electrode in the arc to thereby maintain the arcing tip in substantially the same position at all times. Such mechanisms are usually positioned back of the arc tip and in this position are exposed to the heat radiated

15 and conducted from the arc. In arcs of very high intensity, the heating of the electrode rotating and feeding mechanism may be sufficient to cause warping of this mechanism or cause the mechanism to jam and fail to operate.

20 The heat generated in the arc must be dissipated to prevent injury to the operating mechanisms. Heretofore, arc shields have been provided to shield the mechanism from the arc. Heat radiators have also been used as well as 25 ventilating means to circulate air through the searchlight.

The devices used heretofore have proved inadequate when used with arcs of extremely high intensity such as are used with 60 inch reflectors 30 and which operate at currents of from 150 to 250 amperes and it has been necessary to devise additional and improved protecting means for the electrode operating mechanism.

The object of this invention is to provide a 35 device which shall operate to prevent damage to the electrode operating mechanism of a high intensity arc searchlight due to heat conducted and radiated from the arc.

Another object of the invention is to provide 40 a device which shall operate to minimize the heat conduction from the arc shield to the electrode operating mechanism of a high intensity arc searchlight.

A further object of the invention is to provide 45 a device which shall function to minimize heat conduction from the electrode to the arc shield of a high intensity arc searchlight.

Another object of the invention is to provide a 50 mechanism which shall function to shield the electrode operating mechanism from heat radiation from the arc shield and shall also function as a radiator to dissipate heat conducted from the electrode tip by the electrode.

Another object of the invention is to provide 55 an arc shield for a high intensity arc searchlight

which shall be so shaped as to prevent the arc flame from striking the arc shield.

A further object of the invention is to provide 5 mechanism comprising a plurality of parts, each of which shall function to dissipate a portion of the heat from the arc tip of an electrode of a high intensity arc searchlight, and which shall be so designed as to distribute the burden of dissipation between these parts so as to prevent overheating of any one part. 10

These and other objects and advantages of our invention will be apparent from the following description taken in connection with the accompanying drawing, in which:

Figure 1 is a side elevation view of the arc head 15 of an arc searchlight with parts of the mechanism shown in outline, parts in section, and some parts which are not essential to an understanding of this invention; and,

Fig. 2 is a plan view of the positive electrode 20 holder and associated mechanism of Fig. 1 as viewed from the position indicated by the line II-II of Fig. 1.

In practicing our invention, a frame is provided for supporting a mechanism which operates 25 to feed an electrode to an arc as the electrode is consumed in the arc and to rotate the electrode to insure uniform burning of the electrode and to prevent cracking and chipping of the electrode tip due to the intense heat of the arc. 30 Also mounted upon this frame is a metal sleeve through which the electrode is fed by the feeding and rotating mechanism. Current for operating the arc is conducted to the electrode by brushes which extend through slots in the side of the 35 sleeve and bear upon the electrode.

An arc shield is mounted upon the sleeve to help dissipate the heat from the arc and to shield the operating mechanism from the heat radiated from the arc. This shield is heat- 40 insulated from the sleeve by mica washers which form part of the means for mounting the shield upon the sleeve. The shield has an indentation in its upper side to prevent the shield being damaged by contact with the upwardly extending 45 arc flame. The shield is further protected from damage by heat by spacing the shield supporting sleeve from the electrode so that a layer of gas may be formed and provide heat insulation between these elements. 50

The brush supporting sleeve is also spaced from the electrode to provide heat insulation as just described. The brush supporting sleeve is provided with radiating fins to help dissipate the heat from the electrode and arc. An aux- 55

iliary radiating device is provided to help lower the temperature of the electrode to prevent too great heating of the electrode actuating mechanism. This auxiliary radiating means also serves as a shield to protect the electrode actuating mechanism from the heat radiated from the arc shield.

Referring to the drawing and to Figure 1 in particular, a frame including members 1, 2, 3 10 and 13 (see Fig. 2) is provided for supporting the electrode positioning and actuating mechanisms. The positive electrode is rotated and fed toward the arc by a mechanism 4 which is not shown in detail, since its detailed operation is not 15 an essential part of this invention. This mechanism may be any of the common mechanisms for performing the function of rotating and feeding an electrode and may be such a mechanism as is disclosed in the copending application of I. A. 20 Yost, et al. filed October 3, 1935, Serial No. 43,372 now Patent No. 2,117,888, issued May 17, 1938.

A brushholder 5 is also mounted upon this framework and has brushes 6 extending through 25 slots in the sides of the brushholder and bearing upon the positive electrode. This brushholder is in the form of a sleeve and has fins 7 on its surface to act as radiators to dissipate the heat from the electrode.

30 Auxiliary radiators 8 are provided and these radiators are mounted upon the brushholder 5 by screws 9. These radiator members 8 are spaced by metallic washers 10 to provide ventilating space between the members and to provide 35 heat conducting elements between the members and from the brushholder 5 to the members. These radiator members are in the form of metallic disks and are made of such dimensions as to shield a large portion of the operating mechanism 4 from heat radiated from the member 11.

The member 11 is an arc shield which absorbs and radiates heat from the arc and the electrode and is of such size as to prevent heat radiation from the arc to the operating mechanism 4. Arc 45 shield 11 is secured to frame member 13 by means of bolts 12 (see Fig. 2). Arc shield 11 is insulated from brushholder 5 by mica washer 14 and from frame member 13 by mica washer 15 to prevent conduction of heat from the arc shield to the 50 frame and to the brushholder. This insulation is necessary for the reason that the arc shield, being very near to the arc and to the hottest part of the electrode, becomes very hot in the operation of the arc and it is necessary that this great heat 55 be insulated from metallic members which might conduct the heat to the operating mechanism 4 and thus damage it or cause it to jam.

The arc flame 16 which is formed when an arc 60 is struck between negative and positive electrodes 17 and 18 assumes a form which is approximately that shown in Fig. 1. It will be seen that this flame extends toward the arc shield, and it is necessary that the arc shield be so shaped as to prevent the flame from actually contacting the arc shield. This is done by forming the portion 65 19 of the arc shield in such a manner as to allow the flame to extend upward without striking the portion of the shield as shown in the drawing.

As a means for further providing heat insulation 70 between the positive electrode 18 and the arc shield, the sleeve 20 through which electrode 18 extends and which provides a support for the arc shield is so dimensioned as to space its walls substantially from the electrode 18. This provides 75 a space which fills with gases which are given off

by the highly heated electrode and which serve as a heat insulating layer between the electrode and the arc sleeve. A similar insulating space is provided between the electrode 18 and the brushholder 5 for the same purpose. The filling of these spaces with gases also excludes the air from contact with the electrodes at these points and so prevents burning of the electrodes beyond the arc tip.

In the operation of the device, while the arc is 10 burning, the arc shield 11 absorbs heat from the arc and from the heated end of the electrode and dissipates it from its surface. This provides a medium for reducing the temperature of the electrode in the proximity of the arc shield. The 15 portion of the electrode 18 which extends through brushholder 5 is less hot than that portion which extends through the arc shield sleeve 20, but it is still necessary to dissipate considerable heat from this portion of the electrode to prevent conduction of too great an amount of heat to the electrode actuating mechanism 4. The dissipation of the heat from this area is accomplished by the ribs 7 on the brushholder 5 and the radiating members 8 which constitute the auxiliary radiator 20 and which are secured to the brushholder 5 between the brushholder 5 and the actuating mechanism 4.

The auxiliary radiators 8 are positioned between the brushholder 5 and the actuating mechanism 30 4 to function as a shield to prevent heat radiation from the arc shield 11 and from the brushholder 5 to the actuating mechanism 4. It will be seen that these radiators thus perform the dual function of radiating and shielding.

The mechanism 25 for feeding the negative electrode 17 to the arc is not so complicated as actuating mechanism 4 and is so situated with respect to the arc flame as to require less heat protection from the flame. Means are provided, 40 however, for preventing too great radiation and conduction of heat to this mechanism. These means comprise fins 21 on the brushholder for the negative electrode and auxiliary radiators 22 which have the same construction as radiators 8, 45 a heat insulating washer 23 and metal washers 24.

It will be seen that each of these heat insulating and radiating elements helps to dissipate a portion of the heat from the arc tip and each carries its own share of the burden of dissipating 50 this heat so that the actuating mechanism for the positive and negative electrodes will not be heated to such an extent as to cause it to fail to function.

In compliance with the requirements of the 55 patent statutes, we have shown and described herein a preferred embodiment of our invention. It is understood, however, that the invention is not limited to the precise construction shown and described but is capable of modification by one skilled in the art, the embodiments herein shown being merely illustrative of the principles of our invention.

We claim as our invention:

1. In an electrode positioning and actuating 65 mechanism for a high intensity arc searchlight, a sleeve member having heat radiating fins thereon and having an opening longitudinally therethrough through which the electrode extends, an arc shield through which the electrode extends 70 mounted forwardly of the end of the sleeve member and insulated therefrom by heat insulating material, an electrode actuating mechanism mounted substantially coaxial of and adjacent the other end of the sleeve member, and auxiliary 75

radiating means mounted on the sleeve member between said sleeve member and said actuating mechanism, said auxiliary radiating means being so shaped as to shield said actuating means from heat radiation from said arc shield, the dimensions of said sleeve member and said arc shield being such as to provide substantial spacing between the electrode and the walls of the electrode receiving openings of said shield and sleeve member, said arc shield being formed with a depression in the upper side of its surface which is adjacent the arcing tip of the electrode to prevent the upwardly extending flame from the arc from contacting the arc shield.

2. In an electrode positioning and actuating mechanism for a high intensity arc searchlight, an arc shield comprising a sleeve member surrounding the electrode, a flange member surrounding and extending from the sleeve member substantially normal thereto, said flange portion having a portion thereof displaced away from the arc-tip side so that the flame from the arc may not contact the flange portion.

3. In an arc shield for a high intensity arc searchlight, an imperforate sleeve constituting the supporting hub for said shield, said sleeve having such dimensions as to substantially space the inner walls of the sleeve from the electrode as the electrode extends through the sleeve so as to provide a gas chamber between said sleeve and the electrode.

4. In an arc searchlight, an electrode, an arc shield having a passage through which said electrode extends, a sleeve member through which said electrode extends having heat radiating members thereon, the dimensions of said passage and of the inside of said sleeve being such as to provide substantial spacing between said electrode and said shield and sleeve to thus provide a gas chamber therebetween, and means for securing said shield to said sleeve comprising members of heat insulating material.

5. In an arc searchlight, an electrode, an arc shield having a passage through which said electrode extends, a sleeve member through which said electrode extends having slots through which brushes for conducting electric current to said electrode extend and having radiating fins there-

on, the sleeve and said passage being coaxial and of such dimensions as to provide a substantial gas space between said electrode and said shield and sleeve, and means for securing said shield to said sleeve comprising members of heat insulating material therebetween.

6. In an arcing device, an electrode, means for conducting electric current to said electrode as the electrode is fed to the arc comprising brush means and a sleeve through which said brush means extends to contact the electrode as it passes through the sleeve, said sleeve having heat radiating fins thereon, and an auxiliary radiating means secured to said sleeve comprising plates secured in heat conducting relation with and coaxial of said sleeve.

7. In an arc searchlight, an electrode, means for actuating said electrode, means for conducting electric current to said electrode as the electrode is actuated comprising brush means and a sleeve through which said brush means extends to contact the electrode as it passes through the sleeve, said sleeve having radiating fins thereon and an auxiliary radiating means secured to said sleeve between said sleeve and said actuating means comprising heat conducting plates secured in heat conducting relation with and coaxial of said sleeve, said sleeve being mounted between the arcing tip of said electrode and said actuating means.

8. In an arc searchlight, an electrode, a mechanism for actuating said electrode, an arc shield disposed adjacent the arcing tip of said electrode and between the arcing tip and said electrode actuating mechanism, and a spaced auxiliary heat radiating means disposed between said shield and said actuating mechanism for dissipating heat conducted from said arc shield and said electrode toward said actuating mechanism, said radiating means comprising plates of heat conducting material disposed coaxially of said electrode and extending substantially radially therefrom such a distance as to shield said actuating mechanism from heat radiating from said arc shield.
